R. ANCOTTI AND P. G. MARTONE,
CIRCUIT BREAKER OR CUT-OUT,
APPLICATION FILED FEB. 28, 1917.

1,310,111.

Patented July 15, 1919.

Fig. 1.

UNITED STATES PATENT OFFICE.

RUSSELL ANCOTTI, OF WEST SPRINGFIELD, AND PASQUALE G. MARTONE, OF SPRINGFIELD, MASSACHUSETTS.

CIRCUIT-BREAKER OR CUT-OUT.

1,310,111.

Specification of Letters Patent. Patented July 15, 1919.

Application filed February 28, 1917. Serial No. 151,613.

To all whom it may concern:

Be it known that we, RUSSELL ANCOTTI and PASQUALE G. MARTONE, respectively an Italian subject and a citizen of the United States of America, and residents of West Springfield, and Springfield, respectively, in the county of Hampden and State of Massachusetts, have invented certain new and useful Improvements in Circuit-Breakers or Cut-Outs, of which the following is a full, clear, and exact description.

This invention relates to automatic circuit breakers or cut outs for electrical currents, to be used in various situations, one of which being in electric cars between the power wire and the motor.

The object of this invention is to provide an automatic circuit breaker which, while comparatively of simple and inexpensive construction will be especially effective for preventing or obscuring the spark or flash concurrent with the breaking of the circuit when the tension becomes too high.

Other advantages will be hereinafter rendered apparent.

The invention is described in conjunction with the accompanying drawings and is set forth in the claims.

In the drawings:—

Figures 1 and 2 are sectional elevations of the automatic circuit breaker showing the parts respectively off and on.

Fig. 3 is a sectional view for more clearly showing the relations of contacts and the bridging member included in the apparatus.

Fig. 4 is a partial cross sectional view on a larger scale as taken on line 4—4, Fig. 1, and

Fig. 5 is a partial cross sectional view as taken on line 5—5, Fig. 1.

Referring to the drawings, in which the apparatus is represented as the same has been constructed and operated, A represents a supporting frame which may advantageously be in the form of an inclosing casting. B represents a bar, here represented as slideable vertically through suitable guides a therefor within the casing, or support.

The bar B has a bridging portion or member b to coöperate with contact members d e, the latter being made as swinging levers pivoted at d², e², and having widened extensions for bearing contacts on the bridging portion b.

The bridging portion b has at one end a

block f of insulating material, and one of the contacts, (here the one e) has at its end a block g of insulating material.

These are so provided, as will be seen on comparison of Figs. 1 and 2, that when the device is set, or "on", these insulating portions in no way break or impair the electric connection between the contacts d and e, while when the device is sprung, or "off," and the connection between the contact d and e broken, the insulating portions f and g are brought in engagement and retained in contact relations, that is the swinging members d and e, may not by their springs h be thrown to an improper or blocking relation to the bar.

The bar B has a collar or lug i affixed thereto between which and one of the guides is a spring j in compression and operable to exert a force in an upward direction to the bar.

C represents an electromagnet, of which D is its armature, here shown as hung on the pivot D², and having attached to its upper arm a latch E, which coacts with a shoulder or abutment k carried as a fixed part of the slideable bar B.

When the armature is unattracted to, and off from the electromagnet, the latch E is moved to a position of engagement with the stop k of the drawn down bar B and will hold the latter to maintain relations of the parts represented in Figs. 2 and 3 until the energy of the magnet becomes great enough to attract the armature and effect the latch release and permit the upward movement of the bar.

H represents a cylindrical casing arranged in suitable relation to the bar B and with its axis parallel thereto.

In the lower portion of this casing is a contact member m above which also within the casing is another contact member o which is movable toward and against the contact m and away and to separation from the contact m.

The contact o made in the form of a plunger with the stem p which protrudes through and beyond the top of the casing H, has a spring q applied thereto for forcing the plunger contact o toward and against the fixed contact m.

The stem of the plunger contact has near the upper end thereof a shoulder or abutment s, and the bar B has a laterally ex-

tending arm *t*, which is of apertured or yoké shape, at its extremity, whereby it may have the sliding movement relatively to the stem *p* for a lost motion engagement with the shoulder *s*.

The wiring or electric conductors for this apparatus are pointed out as follows:—

- J represents an insulated wire understood as for taking current delivered from a trolley wire or otherwise and connected with the winding wire of the electromagnet C; K is an insulated wire connecting with the winding wire of the electromagnet and connected with the fixed casing-inclosed contact *m*; L is a conductor connected with the stem of the movable casing-contained contact *o* and with the spring-pressed pivoted contact *d*; and M is an insulated wire connected to and running away from the other spring pressed contact *e*.

Proper insulation is provided between the contacts *o* and *m*, and the inclosing casing therefor, and otherwise in various portions of the apparatus as manifestly necessary; and the cylindrical casing inclosing the last mentioned contacts has a lining *u* of asbestos.

The armature D is provided with an arm *v* to which one end of a spring *v*² is connected, the other end of which spring is secured to a screw *v*³ which threads through a lug *v*⁴ secured to the casing support, and which screw has the capability of endwise adjustments by being turned to vary the tension of the spring, and, consequently, to vary the resistance against the traction by the electromagnet of the armature.

Assuming the parts are set for the "on" or closed condition of the device, as may be done by pulling the bar B downwardly through its handle B², compressing the spring *f* and permitting the latch E to automatically engage the shoulder *k*, and permitting the contact *o* to be forced by its spring *g* onto the contact *m* as represented in Fig. 2, the parts will remain in the relations there shown so long as the electric current passing through the device is not excessive.

An excessive current will so increase the energy of the electromagnet C as to pull its armature to it and cause the disengagement of the latch E from the bar B.

The bar will now be forced upwardly by the recoil of its spring *j*, whereupon the arm *t* will engage the shoulder *s* and force the contact *o*, within the casing H, upwardly against its spring *q* and away from the fixed contact *m*, initially breaking the circuit; and any arc will be extinguished within and by the casing; and substantially simultaneously with this action, but infinitesimally later, the final upward movement of the bar carries the bridging portion *b* so that electrical connection is broken be-

tween the contacts *d* and *e* as will be perceived by the coincident relations of the insulating blocks *f* and *g* in Fig. 1.

It will also be perceived that this apparatus is so organized as to effect an opening of the current conductors in two places, initially between the contacts *o*, *m*, within the casing, and subsequently between the contacts *d* and *e*, such capabilities being deemed desirable in an apparatus of this class. 75

The armature is shown as provided with a stem *w* extended at an accessible place at the exterior of the casing support A, which stem has a handle or push knob.

When the parts of the circuit breaker are closed or on, and the armature off from the electromagnet, Fig. 2, and it is desired to place the device in open condition, this may be done by merely pushing the stem *w* with a sufficient force toward the electromagnet 85 for manually and mechanically accomplishing the last mentioned object.

Considerable latitude of change in the details of construction and the general arrangement of the parts comprised in this device 90 may be made within the scope of our invention, and the device instead of being used in an upright manner as represented in the drawings, may be inverted, turned half way around, or otherwise placed as may be desirable or necessary under any circumstances. 95

We claim:—

1. An overload circuit breaker consisting of a closed box having its interior faces insulated, a fixed sparking member mounted in said box, a movable sparking member in said box adapted to engage a fixed sparking member, a rod connected with said movable sparking member and extending through 100 and insulated from the box, means for holding said movable sparking member normally engaged with the fixed sparking member, an overload magnet electrically connected with the fixed sparking member, an armature for said magnet, a rod connected with the first rod and adapted to separate the movable sparking member from the fixed sparking member, means for moving said rod to separate said contact members, a latch connected with said armature for holding said second named rod against movement, a pair of spaced contact members one of which is connected with said movable contact member and means carried 110 by said second named rod for establishing electrical connection between said contact members when said second named rod is in normal position and adapted to break contact between the contact members when the 115 armature has been attracted by said magnet. 120

2. An overload circuit breaker consisting of a spring actuated rod having a lug thereon, an overload magnet, an armature for said magnet, a latch connected with said armature 130

and adapted to engage said lug to hold said rod under tension, a spring for holding said armature away from said magnet, a pair of spaced contact members one of which is provided with insulation disposed between the members, a bridge piece carried by said rod and adapted to establish electrical contact between said contact members when said latch is engaged with said lug, said bridge piece being provided with an insulation element adapted to register with the insulation of the contact members when said latch is disengaged from said lug, an arm carried by said rod, a closed box the interior of which is completely insulated, a fixed sparking member therein having electrical connections with the magnet, a movable

contact member therein, a rod for said movable contact member extending through and insulated from said box and having slid able connection with the arm of said rod and electrical connection with one of said first named contact members, and a spring for holding said movable member normally engaged with said fixed member in said box, said rod and arm being adapted to separate said movable and fixed members when the latch has been actuated by the magnet.
